LADDER TAPE

James A. Hendley, Middletown, Conn., assignor
to The Russell Manufacturing Company, Mid-
dletown, Conn., a corporation of Connecticut

Application September 20, 1939, Serial No. 295,761

4 Claims. (Cl. 139—384)

This invention relates to improvements in ladder-tapes, which are primarily employed for supporting the slats of so-called "Venetian blinds" and the like, and which comprise a pair of spaced-apart front and back main tapes between which extends transverse textile material constituting the rungs or ladders.

One object of this invention is to provide an improved ladder-tape characterized by maximum strength of anchorage of the ladders in the respective front and back main tapes.

Another object of this invention is to provide an improved ladder-tape at lower cost than the ladder-tapes heretofore in use.

15 Another object of this invention is to provide an improved ladder-tape characterized by superior trueness of the edges of the main tapes and their freedom from unsightly bulges occurring as an incident to the anchoring-in of the 20 rungs or ladders of the tape, and by the outside face of each main tape being of smooth, uniform appearance with no indication of the woven-in anchorage sections of the ladder strands.

25 With the above and other objects in view, as will appear to those skilled in the art from the present disclosure, this invention includes all features in the said disclosure which are novel over the prior art.

30 In the accompanying drawings forming part of the present disclosure, in which only way of carrying out the invention is shown for illustrative purposes:

Fig. 1 is a perspective view of a fragment of 35 ladder-tape made in accordance with the present invention;

Fig. 2 is a view in side elevation of the ladder-tape shown in Fig. 1;

Fig. 3 is a vertical sectional view on line 3—3 40 of Fig. 2;

Fig. 4 is a horizontal sectional view on line 4—4 of Fig. 2;

Fig. 5 is a view in side elevation of the ladder-tape shown in Figs. 1 to 4 inclusive, before the 45 cross-overs have been cut and the ladder-tape opened to the condition shown in Fig. 2;

Fig. 6 is an enlarged broken sectional view on line 6—6 of Fig. 3, while the ladder-tape is in the uncut condition illustrated in Fig. 5, the fragment of ladder-tape being shown in the form of a loop or U in order to accommodate a sufficient length thereof upon the sheet;

Fig. 7 is a fragmental broken sectional view on 55 line 7—7 of Fig. 6;

Fig. 8 is a face view of the opposite side of Fig. 7; and

Fig. 9 is a sectional view on line 9—9 of Fig. 7.

In the description and claims, the various parts are identified by specific names for convenience, but they are intended to be as generic in their application as the prior art will permit.

Referring to the drawings showing the particular form of the invention chosen for illustration, the ladder-tape 10 comprises two main or body tapes 11 and 12 connected together by ladders or rungs 13. One of the main tapes, such, for example, as 11, may be referred to as the front or face main tape, and the other main tape may be referred to as the back or rear main tape. The ladders 13 may be formed of a plurality of parallel strands as shown by weaving the ladder-tape on a two-shuttle loom, or, by employing a four-shuttle loom, the strands can have weft or filling picks interwoven therewith, if desired.

While each of the main tapes could be made of other forms of weaves, the main tapes 11 and 12 in the drawings are shown as formed of a plain type of weave in which single weft or filling strands or picks 14 are woven with groups or pairs of warp strands 15, 15; 15, 16; 15, 17 and 15, 18. The warp strands 15 run continuously throughout the length of the main tapes, whereas the ladder warp strands 16, 17 and 18 do not form continuous warp sections throughout the length of the main tapes.

Thus, by observing Figs. 6, 7 and 8, it will be observed that strands 15, 16 form pairs extending a certain portion or section of the length of a main tape, whereupon the warp section of strands 16 is replaced for the next section or portion by a different warp section of strands 17, and the warp section of strands 17 after extending a certain length or section, is also next replaced by a warp section of strands 18, and the warp section of strands 18 is next replaced by a warp section of strands 16, and so on throughout the length of each main tape.

Instead of forming each weft pick of a single strand portion, it could be formed of a group of two or more strands. Instead of having each group of warp strands consist of a pair of strands, a group of three or more strands could be used in the place of each pair of strands shown in the drawings.

And, while it would not be as advantageous a construction as having at least two strands forming a group as shown in the drawings, a single strand could be used in place of each pair of warp strands shown.

The strands 16 form what may be called one set of warp strands, the strands 17 form another

set of warp strands, and the strands 18 form still another set of warp strands. Each of the sets of warp strands 16, 17 and 18 is successively woven with weft strands of one main tape, then 5 forms a ladder which extends over to the other main tape where it is woven with weft strands of said other main tape, then forms a cross-over to said one main tape where it is woven with weft strands of said one main tape, and so on through- 10 out the length of the main tapes, and therefore may be called ladder-warp strands. Thus, the set of ladder warp strands 16 (Figs. 6 and 7) is woven with weft strands 14 of the main tape 11 to form a woven-in portion or section 16a, then 15 forms a cross-over 16b to the other main tape 12 where it forms another woven-in section 16a, then forms a ladder 16c which extends over to the main tape 11 where it forms another woven-in section 16a, and then forms another cross-over 16b, and so on. Similarly, the set of ladder 20 warp strands 17 successively forms a woven-in section 17a, a cross-over 17b, another woven-in section 17a, a ladder 17c, and so on. And similarly, the set of ladder warp strands 18 success- 25 sively forms a woven-in section 18a, a ladder 18c, another woven-in section 18a, a cross-over 18b, and so on. Each warp strand and weft strand may be composed of a plurality of sub-strands. After the ladder-tape is woven, the cross-overs 30 are cut to permit the tape to be opened up from the position shown in Figs. 5 and 6 to the position shown in Figs. 1 and 2 for use with blind slats in the usual way. Instead of having three sets of ladder warp strands which form the ladders of the ladder-tape, more than three sets of 35 warp strands could be employed.

Each woven-in section of each set of ladder warp strands in a main tape is of substantially-greater length than the distance between the locations 19 of the emergence of each two adjacent ladders from a main tape, so that each woven-in section 16a, 17a, 18a, has overlapping portions 20 in overlapping relation with the warpwise-aligned immediately preceding and im- 40 mediately following sets of ladder warp strands.

By referring to Figs. 7 and 9 it will be seen that the ladder 17c of the set of ladder warp strands 17 at the top of Fig. 7, on entering and becoming part of the overlapping portion 20 with the groups or pairs of warp strands 15, 16, becomes 45 placed or arranged on top of strands 15, 16, in a direction nearer to the longitudinal center line or axis of the ladder-tape than the strands 15, 16, and it will be seen (Figs. 7 and 9) that in the overlapping portion 20, each group or pair of strands 15, 16 has become a group of three strands by the addition of the superposed portion of ladder-strands 17. This is likewise true 50 at each other overlapping place 20 in each main tape.

By having each woven-in section of the three sets of ladder warp strands of considerable length, great strength of anchorage of the ladders is obtained, and this strength of anchorage 65 is still further increased by having the overlapping portions forming each end portion of the woven-in sections. In addition to the increased strength of anchorage of the ladders due to the added length of the overlapping portions, the 70 latter have several additional strength-of-anchorage features. Thus the fact that three strands are crowded in to form a group in each overlapping portion causes a tighter binding-in effect of the weft strands; also the friction anchorage effect of the added third strand on the 75

two other warp strands of a group is greater than if there were only two warp strands in a group in the overlapping portion; and finally, where each third ladder warp strand changes direction at 21 where it turns aside and down, as shown 5 concerning strand 17 (Fig. 7), to become one strand of a two-strand group- or pair-section while one of the lower strands, as shown concerning strand 16, of the three-strand group passes up to form a cross-over, still further increases the anchorage strength of the ladders. Due to the exceptionally strong anchorage of the ladders, I am able to employ a type of weave which is both cheaper and more attractive in appearance than the tighter types of weave which 10 were necessary to use heretofore. The plain type of weave illustrated in the drawings is not only very attractive, but contains less picks or wefts per inch of length and therefore costs less to manufacture. 15

By having one of each group of three ladder warp strands in the overlapping sections on top of two warp strands instead of crowding in between the two bottom warp strands, there is no crowding transversely of the main tapes, and hence the side edges of the main tapes remain 20 true and free from unsightly bulges at the overlapping regions, and the outside face of each main tape is of smooth, uniform appearance with no indication of the woven-in anchorage sections of the ladder strands. 25

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein. 30

I claim:

1. A ladder tape including: first and second main tapes each formed of warp strands woven with weft strands, part of which warp strands of each tape consist of at least three warpwise-aligned sets of ladder-warp strands which sets also form ladders connecting said main tapes and each of which sets is successively woven with weft strands of said first main tape, then forms a ladder as it extends over to said second main tape where it is woven with weft strands 45 of said second main tape, then forms a cross-over to said first main tape where it is woven with weft strands of said first main tape, and so on, each woven-in section of each of said sets of ladder warp strands being of substantially greater length than the distance between two adjacent warpwise-aligned ladders and having portions in overlapping woven relation with the immediately preceding and following woven-in 50 sections of sets of ladder warp strands of a main tape. 55

2. A ladder tape including: first and second main tapes each formed of groups of warp strands woven with weft strands, part of which warp strands of each tape consist of at least three warpwise-aligned sets of ladder-warp strands which sets also form ladders connecting said main tapes and each of which sets is successively woven with weft strands of said first main tape, 70 then forms a ladder as it extends over to said second main tape where it is woven with weft strands of said second main tape, then forms a cross-over to said first main tape where it is woven with weft strands of said first main tape, 75

and so on, each woven-in section of each of said sets of ladder warp strands being of substantially greater length than the distance between two adjacent warpwise-aligned ladders and having portions in overlapping woven relation with the immediately preceding and following woven-in sections of sets of warp strands of a main tape, and substantially each woven-in section of substantially each ladder warp strand of said sets of ladder warp strands forming a section of a said group of warp strands.

3. A ladder tape including: first and second main tapes each formed of groups of warp strands woven with weft strands, a plurality of warp strands of each of said groups of warp strands being arranged side by side in the face of each main tape most distant from the longitudinal axis of the ladder tape, part of which warp strands of each tape consist of at least three warpwise-aligned sets of ladder-warp strands which sets also form ladders connecting said main tapes and each of which sets is successively woven with weft strands of said first main tape, then forms a ladder as it extends over to said second main tape where it is woven with weft strands of said second main tape, then forms a cross-over to said first main tape where it is woven with weft strands of said first main tape, and so on, each woven-in section of each of said sets of ladder warp strands being of substantially greater length than the distance between two adjacent warpwise-aligned ladders and having portions in overlapping woven relation with the immediately preceding and following woven-in sections of sets of warp strands of a main tape, and substantially each woven-in section of substantially each ladder warp strand of said sets of ladder warp strands forming a section of a said group of warp strands.

der warp strands forming a section of a said group of warp strands, and certain of the warp strand portions in said overlapping portions being arranged on top of, and nearer the longitudinal axis of the ladder tape than, said side by side strands.

4. A ladder tape including: first and second main tapes each formed of pairs of warp strands arranged side by side and woven with weft strands, part of which warp strands of each tape consist of at least three warpwise-aligned sets of ladder-warp strands which sets also form ladders connecting said main tapes and each of which sets is successively woven with weft strands of said first main tape, then forms a ladder as it extends over to said second main tape where it is woven with weft strands of said second main tape, then forms a cross-over to said first main tape where it is woven with weft strands of said first main tape, and so on, each woven-in section of each of said sets of ladder warp strands being of substantially greater length than the distance between two adjacent warpwise-aligned ladders and having portions in woven overlapping relation with the immediately preceding and following woven-in sections of sets of warp strands of a main tape, and a portion of substantially each woven-in section of substantially each ladder warp strand of said sets of ladder warp strands forming a section of a said pair of warp strands, and certain of the warp strand portions in said overlapping portions being arranged on top of, and nearer the longitudinal axis of the ladder tape than, said side by side strands.

JAMES A. HENDLEY.

DISCLAIMER
